2 Claims. (Cl. 165—75)

The invention relates to heat exchangers and has among its objects to provide maximum heat transference and high efficiency.

According to the invention there is provided a structure for effecting heat exchange between gases in which the gas to be heated is passed through a first channel which is heated by heated gas flowing in two other channels on each side of said first channel.

According to the invention moreover, a heat exchanger comprises essentially three concentric cylinders mounted to present three adjacent channels, the heating gases being directed through the outermost and innermost channels and the gas to be heated through a channel between the other two channels.

According to the invention furthermore, a heat exchanger is formed as an upstanding cylindrical casing closed at the top and having a lining of refractory material, outer and inner cylindrical sleeves of large diameter concentrically mounted, and positioned to present a narrow annular space between the inner surface of the refractory lining and the outer cylindrical sleeve, and a narrow annular space between the outer and inner cylindrical sleeves, the heating gas, such as flue gas, passing upwardly through the inner cylindrical sleeve and downwardly through the annular space between the outer cylindrical sleeve and the refractory lining, and the gas to be heated passing upwardly through the narrow annular space between the outer and inner cylindrical sleeves.

Access to the inner cylindrical member to effect repairs can easily be obtained by removing the lid closing the top of the heat exchanger.

Thus in the construction according to the invention the heat transfer is effected primarily by convection between the outer cylindrical shell and the surrounding refractory wall and by radiation between the hot gas and the inner shell. The overall efficiency of the heat exchanger is therefore higher than in known heat exchangers.

According to the invention furthermore, the gas to be heated passes from the annular space between the outer and inner cylindrical sleeves to a lateral outlet provided at or near the top of the heat exchanger through a series of radial ports bridging the annular space between the outer cylindrical sleeve and the refractory lining and providing communication between the annular space between the outer and inner cylindrical sleeves and an annular collecting box in communication with the lateral outlet, the downward flow of the heating gases taking place through intermediate vertical passages provided between the ports.

According to the invention furthermore, the outer and inner cylindrical sleeves are supported by and secured to, as by welding, a flanged ring secured to the outer casing of the heat exchanger.

According to the invention furthermore, the radial ports may be formed of a tapering cross-section from top to bottom, to streamline the flow of heating gas past the ports.

The invention further comprises the features of construction hereinafter described.

The invention is diagrammatically and non-limitatively

2

illustrated by way of example in the accompanying drawings, in which:

FIGURE 1 is a sectional elevation of a heat exchanger constructed according to the invention, and

FIGURE 2 is a sectional elevation on an enlarged scale of the top part of the heat exchanger.

In carrying the invention into effect as illustrated in the drawings, the heat exchanger may comprise an upstanding outer metal casing 1 closed by a domed cap 3 and having a lining 2 of a refractory material, a lateral outlet 4 for the heated gas is provided at the upper part and a lateral inlet 5 for the gas to be heated is provided at the lower part of the heat exchanger. At or near the bottom of the heat exchanger is also provided an outlet 6 for the heating gas. Mounted within the casing 1 are two concentric cylindrical sleeves 7 and 8 spaced a short distance apart, the outer cylinder or sleeve being spaced apart from the inner surface of the refractory lining 2 of the heat exchanger. The two annular spaces so formed provide passages for the flow of the heating gases and cold gases to be heated.

The gas to be heated enters the annular space between the outer and inner cylindrical sleeves through the inlet 5 and passes upwardly to be discharged through radial ports 9 into an annular chamber 10 and thence through the lateral outlet 4 provided in the refractory lining of the heat exchanger.

In a typical heat exchanger taken, for example, and without in any way limiting the scope of the invention as claimed, the overall height of the cylindrical shells may be 24 feet; the diameter of the central channel between 3 feet 6 inches and 4 feet 9 inches; the width of the outermost annular channel 2 inches and the width of the intermediate annular channel for the gas to be heated $\frac{3}{4}$ inch to 1 inch. If such a heat exchanger were supplied with heating gas at 1150° C. at a rate of 260,000 cubic feet/hour it would heat 130,000 cubic feet/hour of gas from ambient temperature up to 750° C.

The heating gas, such as flue gas, enters centrally through the bottom of the heat exchanger, the direction of flow of the gas being reversed at the upper end to cause the flue gases to pass downwardly through vertical passages between the radial ports 9, through the annular space between the outer cylindrical sleeve 7 and the inner wall of the refractory lining 2, into an annular chamber 11, and thence to pass out laterally through an outlet 6 provided near the bottom of the heat exchanger.

The cylindrical sleeves 7 and 8 are supported by a flanged ring 12 which is welded to the ports 9 and secured to the outer casing 1. An annular ring 13 of heat-insulating material and of substantially triangular section is secured to the casing 1 to prevent the heated gas from overheating the joint between the outer casing and the domed top.

A heat expansion/contraction joint comprising flexible bellows 14 is provided in the upper end of the heat exchanger for providing a seal between the heated gas outlet and the annular space adjacent the refractory wall of the heat exchanger. Similarly at the lower end of the heat exchanger means are provided to provide a seal between the two annuli, such means taking the form of flexible bellows 15 appropriately mounted.

The radial ports 9 may be formed to a tapering cross-section from top to bottom as illustrated in FIGURE 2 of the accompanying drawings, whereby the downward flow of heating gas past the ports 9 is streamlined.

We claim:

1. A heat exchanger, comprising:
an upstanding cylindrical casing having a lining of refractory material, said casing having a first inlet communicating with the bottom thereof;
a cap removably closing the upper end of said casing;

outer and inner cylindrical sleeves of large diameter mounted concentrically and spaced a short distance apart to provide a narrow first annular space therebetween, said sleeves being positioned within said casing with said outer sleeve being spaced from the inner surface of said lining to provide a second annular space therebetween, the first annular space being closed at the top and open at the bottom, means forming a passage between the interior of the inner sleeve and the second annular space at the upper end of the casing, said inner sleeve extending to the bottom of said casing for communication with said first inlet whereby a heated fluid supplied through said first inlet flows upwardly through said inner sleeve and then downwardly through said second annular space;

means defining a first outlet from said casing adjacent the lower end of said second annular space whereby said heated fluid flowing through said second annular space can be discharged;

means defining a second inlet in said casing communicating with the lower end of said first annular space and isolated from said first inlet and said first outlet whereby a fluid to be heated can be supplied to said first annular space;

means defining a second outlet extending laterally through said casing and communicating with the upper end of said first annular space whereby the fluid to be heated can be discharged from the casing;

a plurality of tubular members secured to and penetrating the outer sleeve at the upper end thereof and extending laterally therefrom;

a flanged ring secured to said tubular members and including a portion which extends outwardly and upwardly to be secured between the cap and the casing whereby the sleeves are supported on the casing and the sleeves can be removed from the casing when the cap is removed; and

a ring of heat insulation material of substantially triangular cross-section disposed between said lining and said portion of said flanged ring above said tubular members to prevent overheating of the joint between the casing and the cap.

2. A heat exchanger, comprising:

an upstanding cylindrical casing having a lining of refractory material, said casing having a first inlet communicating with the bottom thereof;

a cap removably closing the upper end of said casing;

outer and inner cylindrical sleeves of large diameter mounted concentrically and spaced a short distance apart to provide a narrow first annular space therebetween, said sleeves being positioned within said casing with said outer sleeve being spaced from the inner surface of said lining to provide a second annular space therebetween, the first annular space being closed at the top and open at the bottom, means forming a passage between the interior of the inner sleeve and the second annular space at the upper end of the casing, said inner sleeve extending to the bottom of said casing for communication with

said first inlet whereby a heated fluid supplied through said first inlet flows upwardly through said inner sleeve and then downwardly through said second annular space;

means defining a first outlet from said casing adjacent the lower end of said second annular space whereby said heated fluid flowing through said second annular space can be discharged;

means defining a second inlet in said casing communicating with the lower end of said first annular space and isolated from said first inlet and said first outlet whereby a fluid to be heated can be supplied to said first annular space;

means defining a second outlet from said casing at the upper end thereof;

said casing forming an annular chamber at its upper end communicating with said second outlet whereby fluid entering said annular chamber can flow into said second outlet;

a plurality of circumferentially spaced tubular members secured to and penetrating said outer sleeve at the upper end thereof and extending radially outwardly therefrom through said second annular space into said annular chamber and being in fluid communication with said annular chamber whereby fluid flowing through said first annular space can exit therefrom into said annular chamber and thence into said second outlet, said tubular members each having a cross-section which tapers in a downward direction to streamline the flow of heated fluid therewith;

wall means for isolating said annular chamber from said second annular space, said wall means including a flanged ring secured to said tubular members, said ring having a portion which extends upwardly and outwardly to the upper end of the casing whereby said tubular members and said sleeves are supported on said casing;

the flanged ring extending between said cap and said casing whereby said sleeves and said tubular members can be removed from said casing when said cap is removed.
